KARL WILLIAM KOENIGER, OF ORANGE, NEW JERSEY, ASSIGNOR TO THE TURNER TANNING MACHINERY COMPANY, OF PORTLAND, MAINE, A CORPORATION OF MAINE.

HIDE SETTING-OUT AND OILING MACHINE.

Application filed August 30, 1924. Serial No. 735,080.

This invention relates to machines having a tool or tools for operating upon pieces of work, and also means for applying a treating material to one or more surfaces of each 5 piece of work either before or after the operation of the tool or tools.

The invention is illustrated as embodied in a machine for setting the grain surfaces of hides and other relatively large pieces 10 of leather and for applying oil to the grain surface of each hide or piece of leather immediately following the setting operation. While a number of machines have heretofore been proposed for this purpose, none 15 of them has proved satisfactory. Nor have any such machines gone into commercial use so far as applicant is aware. It is still the practice to perform the setting operation upon hides and other pieces of work, utilizing 20 one of the well-known setting machines, and then to apply the oil manually with the aid of a mop or brush. This latter operation is slow and laborious and makes necessary repeated handling of each piece of work.

In view of the foregoing, it is an object 25 of the invention to provide a machine adapted for performing setting operations upon hides or leather and applying treating material to the grain surfaces of the 30 work in such manner as to secure a thorough and uniform application of the material to the work, thus accomplishing the desired results expeditiously and economically in one machine operation. It should be understood, however, that while the invention is 35 herein exemplified as embodied in a machine for setting hides and leather and applying treating material to their grain surfaces, in various aspects the invention is applicable to performing these and similar 40 operations separately as well as in one machine operation.

In accordance with important features of 45 the invention, there is provided means for applying to pieces of work two coats of the treating material in succession, following the operation of a work treating tool, there being a marked improvement in the results attained through the application of a given 50 amount of treating material divided between successive applications as compared with the results obtained upon applying at one operation the same amount of treating material, since in the former case the treating ma-

terial penetrates the work better and with 55 greater uniformity. In the illustrated machine the desired results are accomplished by providing a work-supporting member for presenting hides or leather to a setting tool and to oil-applying means, the member being 60 operated to move in reverse directions whereby the work is presented twice to the oil-applying means after the operation of the setting tool which is rendered inoperative 65 prior to or during the reverse movement of the work-supporting member.

In another aspect the invention resides in the provision of improved means for applying a treating or coating material to pieces 70 of work wherein a rotary material-applying member is arranged to run continuously in one direction to apply the material to the work while the latter is moved in reverse direction whereby the material is applied more thoroughly and uniformly, particularly to 75 pieces of work having pores or other surface irregularities, than has heretofore been possible. Conveniently and as illustrated, a brush is employed to apply oil to hides or 80 leather or other pieces of work and is driven at relatively high speed continuously in one direction during the back and forth movements of the work, the result being that the oil is brushed thoroughly into the work 85 through relative movement of the work and of the brush in the same and in opposite directions. For supplying the brush with the oil there is provided by preference and in the illustrated machine a roll which 90 receives the oil from a reservoir and distributes it upon the brush, an effective driving means for the distributing roll being provided by connections operated in time relation to the work-supporting member so that 95 when the latter member comes to rest the distributing roll ceases to supply the oil to the brush.

In the illustrated machine the work-supporting member is embodied in a drum having a longitudinally extending slot through 100 which a portion of the work may be introduced into the interior of the drum, and in order to prevent access of the oil to that portion of the work within the drum, a shield is provided movable with the drum and operative to bridge the slot and thus 105 prevent the oil from dripping upon the work within the drum.

Other features of the invention and novel combinations of parts will be described in the detailed specification and pointed out in the appended claims.

5 In the drawings.—

Fig. 1 is a partly broken front elevation of a machine embodying my invention;

Fig. 2 is an end view, looking from the left hand side of Fig. 1;

10 Fig. 3 is a detail cross section of the machine;

Fig. 4 is an end view, looking from the right hand side of Fig. 1;

15 Fig. 5 is an enlarged detail plan view of devices at the right hand side of Fig. 1; and

Fig. 6 is an edge view of Fig. 5.

Similar numerals of reference indicate corresponding parts in the several views.

20 The main frame 1 of the machine is of usual construction and at 2 is a shaft journaled in the frame and carrying as a hide supporting member a drum or cylinder 3 disposed horizontally in the frame 1. One side of the member or drum 3 is open or slotted,

25 as indicated at 3^a in Fig. 3. The hide or skin A to be set out or smoothed is hung upon the edge 3^b of drum 3, as indicated in Fig. 3. At 4 is a clamp bar for the hides, which extends parallel to edge 3^b of the drum and is

30 mounted upon spaced arms 5 journaled upon shaft 2. At 6 are stops carried by the frame 1 at opposite ends of the drum to engage with the arms 5 to limit the movement in one direction of the bar 4, whereby when the

35 parts come to rest there will be a space between the edge 3^b of the drum and bar 4 to receive the hide which is subsequently tightly clamped therein. One or more springs 7 are located within the drum, each

40 secured at one end to the drum, at 8, and at its opposite end to bar 4, at 9, which springs serve normally to cause the bar and the edge 3^b of the drum to clamp the hide therebetween. At 10 is a setting and smoothing

45 roll carried by shaft 11 journaled in spaced arms 12 (Fig. 4) which are pivoted at 13 in the main frame above the drum 3. The arms 12 are shown connected by links 14 with a treadle 15 comprising arms 16, shaft

50 17 and crank arms 18 to which the links 14 are connected at their lower ends. Springs 19 (Figs. 2 and 4) interposed between frame 1 and arms 12 serve normally to hold the setting roll 10 yieldingly away from engagement with the drum. Said setting roll is

55 shown provided with worm-like threads 10^a (Fig. 1) disposed in opposite directions from the central portion of the roll, so that when said roll rotates in contact with the surface of a hide or skin A draped over the outer surface of member or drum 3 the roll will set and smooth the skin in spread out condition on the drum.

60 Means are shown for rotating the drum a partial turn in opposite directions for each

hide or portion thereof that is to be operated upon. In the machine illustrated a drive shaft 20 (Figs. 1 and 4) is journaled in suitable bearings in the main frame and is provided with pulley 21 receiving belt 22 from a suitable source of power, said shaft 20 being further provided with pulleys 23, 24 receiving belts 25, 26. The belt 25 passes over a pulley 27 loose on a shaft 28 journaled on the main frame, and belt 26 passes over a pulley 29 loose on said shaft. Shaft 28 carries a pinion 30 in mesh with a drive gear 31 secured on shaft 2 of drum 3. Belt 25 passes direct over pulley 27 and belt 26 is crossed so as to drive pulley 29 reversely to pulley 27, for rotating shaft 28 and drum 3 alternately in opposite directions. A clutch member 32 is slidable on shaft 28 for engagement with pulley 27, and a clutch member 33 on said shaft is also slidable with member 32 for engagement with pulley 29, and said clutch members are keyed to shaft 28, whereby the latter will be rotated in one or another direction according to which clutch member engages pulley 27 or pulley 29. A hub 34 of the clutch members is slid- 70 able on shaft 28 and is operated by a fork 35 (Fig. 4), secured on a shaft 36 journaled in bearings on the main frame, which shaft has a controlling arm 37 extending upwardly and adapted to be engaged alternately by clutch shifting members 38, 39, carried by shaft 2 and disposed at an angle to each other, say at 180°. A lever 40 secured to shaft 36 permits manual control 80 of the clutch members. When the clutch controlling arm 37 is in a central or neutral position neither one of the arms 38, 39 will engage the arm 37, and drum 3 will be at rest. To start the machine the clutch controlling arm 37 is manually shifted so that one of the clutch members 32 or 33 will engage the corresponding pulley to cause rotation of drum 3, and when one of the controlling arms 38 or 39 engages the arm 37 the latter will be rocked to cause uncoupling of one clutch and coupling of the other clutch with the corresponding pulley for reversing the rotation of the drum. The setting roll 10 is rotated by means of pulleys 41 secured on shaft 11 receiving belts 42 from pulleys 43 secured on shaft 20. The parts above described are illustrated as a means of utilizing my improvements for automatically setting and oiling hides in one 90 operation.

95 A rotative brush 44 (Figs. 3, 5 and 6) is carried by a shaft 45 journaled upon the main frame, the bristles of which brush are so located as to bear on and rotate against the hide A that has been set and smoothed out upon drum 3 preparatory to applying oil or other treating liquid to said hide. Shaft 45 of brush 44 may be rotated in any 105 suitable way at relatively high speed when 110

compared with the rate of motion of the work supporting drum. I have shown said shaft provided with a sprocket wheel 46 (Figs. 2 and 4) receiving a chain 47 from a sprocket 48 secured on shaft 20, whereby the brush may be rotated continuously in one direction with shaft 20. Hence the brush applies oil or other treating liquid to the hide in two coats, one while the drum is rotating away from the front of the machine and again upon reverse movement of the drum in returning to initial position. This arrangement results in rubbing in the oil or other treating liquid into the hide in a very thorough manner since by applying the treating liquid first in one direction and then in another the liquid is introduced more effectively into the pores and hair follicles of the hides than it would be by relative movement of the brush and work in one direction only. At 49 (Figs. 3 and 6) is a distributing roll shown carried by shaft 50 journaled in bearings on the main frame, said roll being in position to be engaged by the brush 44 to distribute the treating liquid to the latter. The distributing roll 49 may be fluted or serrated on its surface and is shown operative in a tank or bath 51 supported on the main frame, (Fig. 3). The oil-distributing roll 49 is preferably rotated continuously in one direction and may be driven by any suitable means. I have illustrated ratchet wheels 52, 53 (Figs. 4 and 6) secured upon shaft 50, said ratchet wheels have their teeth disposed in the same direction to be engaged by spring-pressed pawls 54, 55 having their operating ends pointing in the same direction. Pawl 54 is pivotally carried by gear 57 journaled upon shaft 50, and pawl 55 is pivotally carried by a gear 56 journaled on shaft 50. As shown gear 57 is in mesh with pinion 58 journaled at 59 and attached to and operated by gear 60 in mesh with gear 31. Conveniently gear 56 is driven directly from gear 31. When gear 31 rotates in one direction with the drum 3 the pawl 55 will rotate shaft 50 and the oil distributing roll 49 in one direction, and when the gear 31 and drum 3 rotate in the reverse direction the other pawl 54 will rotate shaft 50 and oil distributing roll 49 in the same direction, as before so that said roll will be rotated always in one direction. Moreover, when the drum is stationary the fluted roll 49 is also stationary so that oil is not lifted from the tank 51 and wasted while no work is being done. The ratio of gearing shown for rotating oil distributing roll 49 may be varied for any desired speed of rotation of said roll.

A flexible shield or apron 61 (Fig. 3), of suitable material impervious to oil and other treating liquids, is shown disposed in the opening 3^a between the edge 3^b of the drum 3 and the hide-clamping bar 4, to which the

corresponding edges of the shield or apron 61 are secured in any suitable manner. The shield or apron 61 is sufficiently flexible to enable bar 4 to move to open position, and subsequently to closed position to engage the hide resting upon the edge 3^b of drum 3. The shield or apron will catch the drippings of oil or other treating liquid from brush 44 so as to prevent the oil from passing down into the interior of drum 3, hence keeping such oil from engagement with the portion of hide A that hangs within said drum from the edge 3^b, so that the hide will not be smeared with or injured by waste or undersired oil.

A shield 51^a is shown depending below tank 51 to protect the outer surface of the drum from drippings.

Since the portion of each hide exposed for treatment on the surface of the drum is different in size and in shape in each succeeding operation, it follows that the area of the work supporting surface of the drum covered by the portion of the hide arranged for treatment by the roll 10 and brush 44 will be much less in some cases than in others, and since the drum is always rotated to the same extent irrespective of the size of the piece of work presented for the operation of the roll 10 and of the liquid applying brush 44, it follows that treating liquid will be applied by the brush to uncovered portions of the drum of variable area during repeated operations of the machine, the said uncovered portions being of considerable extent where the pieces of work are smaller than usual. Hence, during operations of the machine, the blades of the roll 10 in contacting with the uncovered surface of the drum wet with oil or other treating liquid will pick up in time a considerable amount of treating liquid. Even if the pieces of work, that is, the hides, be of a selected lot of substantially the same size, the edge contour of each is different from that of every other, thus leaving uncovered portions of the drum surface of irregular and variable area. Hence, oil or other treating liquid will be applied by the brush to the irregularly-shaped uncovered portions of the drum surface from which it is subsequently removed by the blades of the roll 10. To prevent spattering of oil or other treating liquid, upon the work and upon the operator, from the roll 10 a shield 62 is suitably supported upon the main frame and arranged to extend over and in front of the setting roll 10. The lower portion of the shield 62 adjacent to bar 4, (Fig. 3), is provided with a channel or gutter 63, located along the inner lower edge of the shield to catch oil drippings from within the shield. Any suitable outlet tube may lead from the gutter 63 to a receptacle for the drippings.

In the operation of the illustrated embodiment of my invention the hide to be set out and oiled is hung upon the edge 3^b of drum 3, as illustrated in Fig. 3, and the machine 5 started. As the drum rotates in the direction of the arrow in Fig. 3 the edge 3^b will force the adjacent part of the hide against bar 4, whereby the hide will be clamped by the tension of springs 7. Continued rotation 10 in said direction of drum 3 carries the outer portion of the hide on the drum in contact with the setting roll 10, the operator operating the pedal 15 downwardly at the appropriate time, against the tension of the 15 supporting springs 19 (Figs. 2 and 4), to bring the roll 10 into contact with the hide. As the hide travels with the drum beneath roll 10 the rotation of the latter causes setting and smoothing of the hide in an extended condition on the outside of the drum and then the drum carries the hide forwardly into engagement with brush 44, which will rotate in contact with the hide and apply oil thereto. When the oil has 25 been applied upon the hide the drum 3 will reverse its direction of rotation, by means of the operation of the clutch devices hereinbefore described, and the operator will release the treadle so that roll 10 will be 30 lifted from the hide by the springs 19 (Fig. 2) in order that the outer or oiled portion of the hide may be left in its oiled and set condition and not have any portion of the oil removed by the bladed cylinder nor the 35 surface of the hide operated upon by a cylinder moving in the wrong direction relatively to the work. During this reverse movement of the drum, the brush 44 applies the second coat of oil and rubs it in 40 thoroughly during the reverse relative movement of the drum and brush. As usual in this class of machines, the hide will be removed from the drum and reversed as many times as required to present its several 45 surfaces on the exterior of the drum to be set and oiled each time that the drum rotates back and forth to carry the set and smoothed hide in contact with the oiling brush. Any time that the surface of the exposed portion 50 of the hide has been oiled during rotation of the drum from front to rear, the drum may be reversed by the operator by shifting the member 37 whereupon the drum returns to initial position for shifting of the hides 55 or applying new hides.

In accordance with my invention I am enabled with one placing of a hide in the machine to set and oil its exposed surface while it is upon the drum, and the oiling 60 will be effected in a smooth and uniform manner with a great degree of accuracy and with a minimum loss of oil whereby the operation of setting and oiling hides and skins is expedited and the cost reduced with 65 resultant uniformity of production.

While I have referred to the application of oil to hides it will be understood that the machine may be used for applying other suitable material than oil to hides or skins, and that the term "oil" as used in the 70 specification and claims is intended to include such other material.

Having now described my invention what I claim is:

1. A machine of the character specified 75 comprising a member to support hides, means to removably secure the hides to said member, means to set out the hides on said member, mechanism to actuate said member with respect to said setting out means, and means to apply oil to the set out hides.

2. A machine as set forth in claim 1, in which the means for applying oil to the set out hides comprises a rotative brush, and 80 means to supply the brush with oil.

3. A machine of the character specified comprising a rotative member to receive hides, means to removably secure the hides to the member, setting out means cooperative with the member to set out the hides, means 90 to actuate said member and setting out means, and means to apply oil to said set out hides.

4. A machine as set forth in claim 3, in which the means for applying oil to the set 95 out hides comprises a rotative brush, and means to supply the brush with oil.

5. A machine of the character specified comprising a member having an opening in one side to receive hides, means to removably 100 secure hides to the member, a flexible shield disposed with respect to said opening of the member, means to set out hides upon the member, and means to apply oil to the set out hides on the member, said shield being 105 located in such position as to obstruct entrance of oil through said opening into the member.

6. A machine as set forth in claim 5, in which the means for applying oil to the set 110 out hides comprises a rotative brush, and means to supply the brush with oil.

7. A machine of the character specified comprising a rotative drum having an opening at one side, a bar co-operative with the 115 drum to removably secure hides thereto, means cooperative with the drum to set out the hides, a flexible shield connected with the drum and with said bar adjacent to said opening, and means to apply oil to the set out 120 hides on the drum, said shield being located in position to obstruct oil from entering the drum through said opening.

8. A machine of the character specified comprising a rotative drum having an opening in one side, clamping means to removably secure hides to the drum, a setting out roll cooperative with the drum to set out 125 hides thereon, a rotative brush to apply oil to the hides set out on the drum, an oil- 130

distributing roll for the brush, an oil supply tank for the roll, and means to operate said parts.

9. A machine as set forth in claim 8, provided with a shield extending at one side of the drum and beneath the oil tank.

10. A setting out machine comprising a drum for hides, means to removably secure hides to the drum, a setting out roll, a shield 10 partially around said setting out roll, and means to apply oil to set out hides on the drum.

11. A machine as set forth in claim 10, in which said shield is provided with a gutter 15 below the setting out roll to collect oil therefrom.

12. A machine for setting out hides comprising a drum, means to removably attach hides to the drum, means to rotate the drum 20 in opposite directions, a setting out roll cooperative with the drum to set out hides thereon, a rotative brush to apply oil to the hides on the drum, an oil-distributing roll for the brush, means to rotate the brush, 25 means cooperative between the drum and the oil-distributing roll for rotating the latter in one direction during reciprocations of the drum, and means to supply oil for said oil-distributing roll.

30 13. In a machine of the character described, a drum for supporting a piece of work, a tool for operating on the work during rotation of the drum in one direction, and means for applying a treating material 35 to the work during movement of the drum first in one direction and then in the reverse direction back to initial position whereby two coats of the treating material are applied in succession to the work.

40 14. In a machine of the character described, a member for supporting a piece of work, a tool for operating on the work presented by the member, means for applying a treating material to the work, means for 45 moving the work supporting member first in one direction and then in the reverse direction to secure the application to the work of two coats of the treating material in succession, and means for moving the tool away 50 from the work prior to the reverse movement of the work supporting member.

55 15. In a machine for setting and oiling hides and other pieces of work, a member for supporting a hide or other piece of work, a tool for setting and spreading the hide or other piece of work presented by the member, means for applying oil to the work, means for moving the work supporting member to present the work to the tool and 60 to the means for applying the oil and for reversing the direction of movement of the member to bring the latter back to initial position whereby the work passes the oil applying means twice to receive two coats 65 of the oil in succession, and means for caus-

ing the setting and spreading tool to operate while the rotary member is moving in one direction only.

16. In a machine of the character described, a rotary member for supporting a piece of work, a tool for operating on the work presented by the rotary member, a roll for applying a treating liquid to the work, means for rotating the work supporting member to present the work to the tool and to the applying roll and for reversing the direction of movement of the rotary member to bring the latter back to initial position whereby the work receives two coats of the treating liquid in succession, and means under the control of the operator for causing the tool to operate while the rotary member is moving in one direction only. 70

17. In a machine of the character described, a drum for supporting a piece of work, means for oscillating the drum alternately in opposite directions, a tool for operating on the work supported by the cylindrical surface of the drum, a brush rotatable continuously in one direction in contact with the work on the drum, a liquid containing tank, a roll for removing the treating liquid from the tank and distributing it to the brush, and means operated from the drum for rotating the distributing roll continuously in one direction during oscillations of the drum. 80

18. In a machine for setting and oiling hides and other pieces of work, a member for supporting a hide or other piece of work, a tool for setting and spreading the hide or other work presented by the member, means for applying oil to the hide or other work, means for moving the work supporting member first in one direction and then in the reverse direction to secure the application of two coats of the oil in rapid succession, and means under the control of the operator effecting operation of the setting tool during movement of the work supporting member in one direction only. 90

19. In a machine for setting and oiling hides and other pieces of leather, a drum for supporting a hide or other piece of work and having an opening therein for receiving a portion of the hide or other work within the drum, means movable in the opening for temporarily securing the hide or other work to the drum, a tool for setting and spreading the hide or other work during rotation of the drum in one direction, and means for applying oil to the set and spread surface of the hide or other work during movement of the drum first in one direction and then in the reverse direction back to initial position whereby two coats of oil are applied in succession to one surface of hide or other work. 100

20. In a machine for setting and oiling hides and pieces of leather, a drum for sup- 110

- porting a hide or other piece of work, a tool for setting and spreading a hide or other piece of work on the surface of the drum, means for oscillating the drum first in one direction and then in the other, and a roll rotatable continuously in one direction for applying oil to the set and spread surface of the hide or other work during oscillation of the drum in both directions, and means under the control of the operator for effecting operation of the setting tool during movement of the drum in one direction only.
21. In a machine for setting and oiling hides and other pieces of leather, a drum for supporting a hide or other piece of work, means for oscillating the drum first in one direction and then in the reverse direction, a tool for setting and spreading the hide or other piece of work supported by the cylindrical surface of the drum, a brush rotatable continuously in one direction in contact with the hide or other work on the drum, an oil containing tank, a roll for removing the oil from the tank and distributing it to the brush, means operated from the drum for rotating the distributing roll continuously in one direction during oscillation of the drum, and means for controlling the tool so that it operates upon the hide or other work during movement of the drum in one direction only, while the brush applies the oil during both of the oscillatory movements of the drum.
22. In a machine for applying a treating or coating material to a surface of a piece of work, a work-supporting member, means for oscillating the member in reverse directions, and a member rotatable continuously in one direction for applying material to a surface of the piece of work during oscillation of the work-supporting member, whereby a plurality of coats of the material is applied to the work during the operation of the machine.
23. In a machine of the character described, a drum for supporting a piece of work, means for oscillating the drum first in one direction and then in the other, and a brush rotatable continuously in one direction for applying a treating liquid to the work during the oscillation of the drum in both directions.
24. In a machine of the character described, a work supporting member having an opening therein to receive a portion of the work, means for operating on the work comprising means for applying a treating

liquid thereto, and a shield movable with the work supporting member for preventing the treating liquid from entering the opening to fall upon the portion of the work introduced through the opening.

25. In a machine of the character described, a work supporting member having an opening therein to receive a portion of the work, means for removably securing the work to the member, means for operating on the work comprising means for applying a treating liquid thereto, and a shield arranged to co-operate with the work securing means to close the opening in the member to protect that portion of the work introduced through the opening.

26. In a machine of the character described, a work supporting member having an opening therein to receive a portion of the work, means for operating on the work comprising means for applying a treating liquid thereto, and a flexible shield operative to bridge the opening in the work supporting member to protect the portion of the work introduced through the opening in said member.

27. In a machine of the character described, a rotary member for supporting a piece of work, said member having an opening through which a portion of the work is introduced, a clamping member movable in the opening for clamping the work to the rotary member, means for operating on the work comprising means for applying a treating liquid to the work, and a flexible shield attached to the rotary member and to the clamping member and operative to protect that part of the work introduced through the opening in the rotary member from access thereto of the treating liquid.

28. In a machine of the character described, a rotary member for supporting the work having an opening for the introduction of a portion of the work, a clamping member movable in the opening for clamping the work to the member, means for operating on the work comprising means for applying a treating liquid to the work, means for moving the rotary member in one direction to pass the work under the treating means and for reversing the movement of the rotary member to effect a second application of the treating liquid, and a shield movable with the rotary member to prevent access of the treating liquid to that portion of the work disposed within the rotary member.

KARL WILLIAM KOENIGER.
